[57] CLAIM

The ornamental design for the electric toothbrush holder, as shown and described.

DESCRIPTION

FIG. 1 is a front elevational view of an electric toothbrush holder, showing our new design;
FIG. 2 is a right side view thereof, the left side view being a mirror image thereof;
FIG. 3 is a top view thereof;
FIG. 4 is a rear view thereof;
FIG. 5 is a bottom view thereof; and
FIG. 6 is a left side elevational view thereof, shown with the support hook pivoted to an alternate position.

FIG. 2

FIG. 1

FIG. 3

FIG. 4

FIG. 5

FIG. 6
